F. SCHMIDT

INTERNAL COMBUSTION ENGINE

Filed March 17, 1921

UNITED STATES PATENT OFFICE.

FRED SCHMIDT, OF CHICAGO, ILLINOIS, ASSIGNOR, BY DIRECT AND MESNE ASSIGNMENTS, TO MAJOR ENGINEERING CORPORATION, A CORPORATION OF ILLINOIS.

INTERNAL-COMBUSTION ENGINE.

Application filed March 17, 1921. Serial No. 453,109.

To all whom it may concern:

Be it known that I, FRED SCHMIDT, a citizen of the United States, residing at Chicago, in the county of Cook and State of Illinois, have invented certain new and useful Improvements in Internal-Combustion Engines, of which the following is a specification.

The invention relates to improvements in internal combustion engines of the turbine type and associated air compressors.

An object is to provide a turbine engine having a rotor arranged to be driven by impact of the exploding charges projected from a contiguous combustion chamber.

Another object is to provide a structure having a combustion chamber in which an explosion takes place and in which the valve is automatically opened by the effect of the explosion to permit the products of combustion to be projected against the peripheral surfaces of an associated rotor.

Another object is to provide, in an engine of the character described, a casing containing a combustion chamber having an admission valve which automatically opens as a result of the pressure of the charge to admit the charge into the combustion chamber and another valve that automatically opens by the effect produced by the explosion, to permit the products of combustion to strike the peripheral surfaces of the rotor at suitable intervals to drive the same.

Another object is to provide means for introducing steam or vapor into the exploded charge after it leaves the combustion chamber and before it strikes the rotor.

Other, further and more specific objects of the invention will become readily apparent, to persons skilled in the art, from a consideration of the accompanying drawings, wherein:

Fig. 1 shows a central sectional view of one of the large casings, or bottles, containing a combustion chamber, within which the explosions occur.

Fig. 2 is a section taken on line 2—2 of Fig. 1.

In all the views the same reference characters are employed to indicate similar parts.

The casing 75 is provided with a flange 82, having holes 83 thru which cap screws 84 may be inserted to secure the casing to the frame of the engine. The casing or

bottle 75 is provided with a head 85, screw threaded as at 86 for insertion in the end of the casing. The head 85 is also provided with an integral interior projecting guide tube 87. The head is also bored, as at 88, for a piston head 89 which is the terminal end of the tube 87 and the head 89 moves freely in the bore 88. The valve is held closed by an open helical spring 91, the strength of which may be adjusted by the screw plug 94.

The piston 89, of the valve 79, is larger than the tubular portion 90 of the valve, and at intervals around the bore 88 are a series of perforations or holes 93 opening from the interior of the bore to the interior of the bottle or the combustion chamber 76.

A spark plug 92, threaded into the casing 75, near the port 78 thru which the products of combustion are discharged upon the occasion of an explosion of the combustion chamber, is screwed into the casing and is provided with terminals 95. The casing 75 is provided with a hub 96 which is internally screw threaded, as at 97, and into which a plug 98 is screwed carrying a check valve 99, normally closed by the spring 100.

The fuel charges consisting of the proper admixture of air and suitable quantity of gasoline vapor comes thru the pipe 101 from the compressors and is delivered into the combustion chamber 76 by the self-opening puppet valve 99.

The spring 100 is set so that when the pressure of the charge to be injected into the combustion chamber 76 is sufficient to overcome the resistance of the spring, the chamber is filled with an explosive mixture under pressure. Just at the time when the pressure is at maximum value a spark is produced at the terminals 95 of the spark plug 92, whereupon an explosion will take place in the chamber 76. The effect of the explosion is to open the valve 79 by the pressure applied to the piston 89 of the valve 79 thru the openings 93. Immediately upon the opening of the valve 79, the products of combustion will pass out with considerable force, thru the nozzle 80, and impinge upon the cups of the rotor, thereby causing the rotor to revolve at high velocity.

A water supply pipe 102 leads from a suitable source of supply and is connected to the valve 103 which may be opened, to a greater or less extent, by rotating the handle 110

104 to admit the desired quantity of water into the combustion chamber 76.

A tube 105 is perforated at its inner end, as at 106, to distribute the water in the tube 90 of the valve 79. As the products of combustion leave the combustion chamber 76 thru the nozzle 80 with considerable force and at high velocity, it produces a vacuum effect in the tube 90 of the valve 79 and causes water to be drawn into the tube which is converted into steam by the hot surfaces of the tube 90 and which goes out with the next charge that leaves the combustion chamber 76. By this means water or steam which is more ponderable than the gases of explosion is carried with forcible effect against the peripheral surface of the rotor.

The power thus produced is much greater than it otherwise would be without the assistance of the water. The water furthermore has the effect of keeping the combustion casing 75 relatively cool so as to prevent spontaneous explosion. While the engine will run with fair efficiency without the water for a protracted period of time without dangerous heating, it is believed that the

water contributes to produce a higher efficiency, its expansion into steam contributing to the force of the impact.

Having described my invention what I claim as new and desire to secure by Letters Patent, is—

A combustion chamber and nozzle for turbine gas engines comprising a bottle-like casing having a nozzle opening thru a port into a combustion chamber in the casing; a hollow tubular valve to close the port, extending axially thru the chamber and having a piston on its outer end axially movable in a cylinder therefor, provided in the casing; an adjustable spring to yieldingly hold the valve normally seated on said port but permitting the valve to open the port by pressure generated by the explosion of gases within the casing and a pipe within the tubular valve, whereby to introduce water therein by the suction effect produced by the heated gases thru said port.

In testimony whereof I hereunto subscribed my name.

FRED SCHMIDT.
